(57) **CLAIM**

The ornamental design for a media player device, as shown and described.

DESCRIPTION

FIG. 1 is a front elevation view of a media player device.

FIG. 2 is rear elevation view thereof.

FIG. 3 is a first side elevation view thereof.

FIG. 4 is a second side view thereof.

FIG. 5 is a top plan view thereof.

FIG. 6 is a bottom plan view thereof.

FIG. 7 is a first perspective view thereof; and,

FIG. 8 is a second perspective view thereof.

The even broken lines illustrate portions of the article that form no part of the claimed design. The dot-dash broken lines illustrate boundaries of the design, and form no part thereof. The surfaces within the dot-dash boundary lines located on the face of each of the two circular features of each of the two stadium-shaped features form no part of the claimed design. The entire bottom surface up to the solid line perimeter also forms no part of the claimed design.
